UNITED STATES PATENT OFFICE.

JOHN J. McKEE, OF EAST ORANGE, NEW JERSEY.

DESIGN, FOR A NAVAL SERVICE-FLAG.

55,069.

Specification for Design.

Patented May 4, 1920.

Application filed August 31, 1918. Serial No. 252,265. Term of patent 7 years.

To all whom it may concern:

Be it known that I, JOHN J. McKEE, a citizen of the United States, residing at East Orange, in the county of Essex and State of New Jersey, have invented a new, original, and ornamental Design for Naval Service-Flags, of which the following is a specification, reference being had to the accompanying drawing, forming part thereof.

In the drawing the figure is a plan view of the flag.

I claim:—

The ornamental design for a naval service flag, as shown.

JOHN J. McKEE.
